UNITED STATES PATENT OFFICE.

BIRNEY K. SMITH, OF ELWOOD, INDIANA, ASSIGNOR OF ONE-HALF TO JOHN E. DAVIS,
OF ELWOOD, INDIANA.

LIGHT-DIFFUSER FOR HEADLIGHTS.

1,283,935.

Specification of Letters Patent.

Patented Nov. 5, 1918.

Application filed September 17, 1917. Serial No. 191,678.

To all whom it may concern:

Be it known that I, BIRNEY K. SMITH, a citizen of the United States, residing at Elwood, in the county of Madison and State of Indiana, have invented certain new and useful Improvements in Light-Diffusers for Headlights, of which the following is a specification.

This invention relates to a device for diffusing the projected rays of light without interfering with the incident and reflected rays of light projected parallel with the axis of a lamp having a parabolic reflector, thereby rendering my device particularly applicable for use in connection with the head lights for motor cars.

One of the objects of the invention consists in the provision of a device of the above character, by which the rays of light are uninterruptedly projected forward parallel with the axis of the lamp, while the angularly projected rays of light are sufficiently diffused so as to not obscure the vision of persons approaching from the opposite direction.

A further object of the invention consists in the provision of a device of the above character, which is simple in construction, efficient in operation, and inexpensive to manufacture.

I accomplish the above objects of the invention, and such others as may appear from a perusal of specification and claims, by means of the construction illustrated in the accompanying drawings, forming a part hereof, in which—

Figure 1 is a front elevation of my invention, in which the frame of the usual head light is omitted. Fig. 2 is a fragmentary detail view of the rear side of the rim showing the manner in which the radial blades are secured. Fig. 3 is a central vertical section through an ordinary head light for motor cars, showing my invention in operative position. Fig. 4 is a side elevation of one of the blades, the remaining parts of the device being omitted.

Referring to the drawings, 10 represents the parabolically shaped shell of an ordinary and well known head light employed on motor cars, the inner surface of shell 10 affording the surface for a parabola reflector. The outer marginal edge of shell 10 is bent outwardly and is thence bent for-

wardly into an annular flange 11. Arm 55 is ranged within flange 11, and the open front of shell 10, is a lens 12 which is retained in operative position by the usual annular collar 13. A lamp 15 is arranged in the axis of shell 10, and said lamp is mounted in a suitable socket 16.

Means for diffusing the projected rays of light from lamp 15 comprises a plurality of radially arranged blades 20. The outer ends of blades 20 are uniformly spaced and are secured to an annular ring 21, and this ring is arranged immediately back of lens 12 and within shell 10, and is held by the pressure exerted by ring 21. Blades 20 do not extend to the axis of shell 10 but are reduced in length a sufficient distance to provide clearance for lamp 15 so that the inner ends of blades 20 extend circumferentially about said lamp, as shown. In order to hold the inner ends of blades 20 a uniform distance apart, I pass a supporting means through each of said blades, which means may comprise a wire 22 to form a central support or hub for the blades, and is arranged in the rear and surrounds the light source 15. The forward points of the inner ends of blades 20 are also maintained a uniform distance apart by support 23 which is similar to support 22. The radial arrangement of blades 20, their width, together with the relative position of lamp 15, causes blades 20 to intercept and diffuse the projected rays of light from lamp 15, thereby eliminating the glare outside of a limited area illuminated by the incident and reflected rays from the reflector which rays are projected parallel with the axis of lamp 15.

By means of this construction a person approaching the lamp at an angle which is oblique to the plane through the horizontal axis of the lamp will not be blinded by the direct rays of light. Looking directly into the axis of lamp 15, radial blades 20 present practically no barrier, the rays of light being projected freely in advance of the lamp, so that the roadway directly ahead of the motor car is sufficiently illuminated to enable the driver to note the condition of the roadway.

I claim:

1. A vehicle light comprising a concave reflector having its axis horizontal, means for supporting a lamp in said reflector, a

108

2
hub surrounding the lamp for supporting the rear ends of a plurality of radial blades, and a plurality of blades radially arranged around the hub surrounding the lamp, said 5 blades increasing in width as they approach the horizontal axis of the reflector for intercepting the direct rays of light from the lamp.

2. A vehicle light comprising a concave reflector having its axis horizontal, means 10 for supporting a lamp in said reflector, a hub surrounding and arranged back of the lamp, and a plurality of uniformly spaced radial blades supported by said hub with 15 the major width of the blades adjacent the lamp extending from the hub to a point in advance of the lamp and diminishing in

width as they approach the outer marginal edge of the reflector.

3. A vehicle light comprising a concave 20 reflector having its axis horizontal, means for supporting a lamp in said reflector, a hub extending circumferentially around the lamp, a plurality of blades extending radially from said hub with the major width 25 of the blades adjacent the lamp, and means for supporting the outer ends of the blades a uniform distance apart.

In witness whereof, I, have hereunto set my hand and seal at Indianapolis, Indiana, 30 this 11th day of September, A. D. one thousand nine hundred and seventeen.

BIRNEY K. SMITH. [L.S.]
